UNITED STATES PATENT OFFICE.

EDWARD P. POOR, OF SCRANTON, PENNSYLVANIA.

DESIGN FOR A COMBINED TOILET AND WRITING STAND.

Application filed October 17, 1923. Serial No. 7,522. Term of patent 3½ years.

To all whom it may concern:

Be it known that EDWARD P. POOR, a citizen of the United States, residing at Scranton, in the county of Lackawanna and State of Pennsylvania, has invented a new, original, and ornamental Design for Combined Toilet and Writing Stand, as shown in the accompanying drawing and described in the following specification.

I claim:

The ornamental design for combined toilet and writing stand as shown.

EDWARD P. POOR.
